UNITED STATES PATENT OFFICE.

GEORGE H. BARGE, OF PHILADELPHIA, PENNSYLVANIA, ASSIGNOR TO
WILLIAM WHARTON, JR., AND COMPANY, INCORPORATED, OF SAME
PLACE.

RAIL-FASTENING.

SPECIFICATION forming part of Letters Patent No. 388,241, dated August 21, 1888.

Application filed May 4, 1888. Serial No. 272,771. (No model.)

To all whom it may concern:

Be it known that I, GEORGE H. BARGE, a citizen of the United States, and a resident of Philadelphia, Pennsylvania, have invented 5
certain Improvements in Rail-Fastenings, of which the following is a specification.

The object of my invention is to so construct a combined tie-plate and brace-piece that on spiking the tie-plate down the brace-piece will tend to bind firmly upon the rail, and I so construct the parts that the downward pressure of the rolling-stock will tend to increase the pressure of the brace-piece upon the rail.

15 In the accompanying drawings, Figure 1 is a side view of my improved combined tie-plate and brace-piece, with the rail in section. Fig. 2 is a view showing the brace-piece thrown back and the rail being inserted or re-20 moved. Fig. 3 is a detached perspective view of the tie-plate, and Fig. 4 is a detached perspective view of the brace-piece.

A is the rail, of the ordinary T shape, but it will be understood that any form of rail may 25 be used with the device.

B is the tie-plate; D, the brace-piece. E E' are the securing spikes or bolts, and F is the wooden cross-tie, although it will be understood that metallic or other forms of cross-ties 30 may be used without departing from my invention.

I prefer to make the tie plate of sheet metal struck up into the form required, and for this purpose I cut out two sections and strike 35 them up to form lips b b, which overlap one of the base-flanges of the rail. I strike up from the opposite side of the base-plate B a lip, c, to the position shown, thus forming an opening, c', through which the tail-piece d of the brace D can be inserted. This tail-piece 40 is somewhat thicker than the tie-plate, so that when the tail-piece is in the position shown in Fig. 1 the lip c will bear upon it, and it will be tightly secured between this lip c and 45 the tie F when the plate B is secured to the latter by means of the spikes E E'.

The brace-piece D has a face, d', which rests against the web of the rail, and preferably,

as shown in Fig. 1, against the upper corner of the rail, so that it will not only take the 50 side-thrust, but also the compression-thrust, of the weight of the rolling-stock. The brace-piece has a suitable web, e, which tends to strengthen said brace-piece, this web extending down through an opening, c', in the 55 struck-up lip c. This brace-piece is so formed as to provide a ledge, e', which overlaps the base-flange of the rail A.

It will be understood that instead of the struck-up sheet-metal tie-plate B, a cast tie-60 plate may be used; but I prefer, for the sake of cheapness, to use the struck-up sheet-metal tie-plate.

The rail being placed in position, as shown in Fig. 2, the tail of the brace-piece is then 65 inserted through the opening c', and the brace is moved in the direction of its arrow to the position shown in Fig. 1, and after the gage has been set the plate is spiked down, clamping the tail-piece of the brace between the 70 struck-up lip c and the tie, thus firmly securing it in position. When the pressure of the rolling-stock comes on the rail, it will press upon the tie-plate, and consequently through the tie-plate upon the tail of the 75 brace-piece, thus tending to more securely lock the brace-piece to the rail while the rolling-stock is passing over. To remove the tie-plate from the rail, the spikes are withdrawn and the plate slipped to one side of the tie, 80 which will allow the brace-piece to be removed, as shown in Fig. 2, after which the rail can be removed, as indicated in said figure, and a new rail inserted.

I claim as my invention—

1. The combination of the rail with the tie-plate having lips overlapping one side of the base-flange of the rail, and having a raised lip and opening on the opposite side of said base-flange, with a brace-piece adapted to bear 90 against the rail, and having a tail-piece adapted to said opening and confined to the rail by said lip of the tie-plate, all substantially as set forth.

2. The combination of the rail, the tie-plate 95 having lips overlapping the base-flange of the

rail, and having a raised lip, *c*, and opening *c'*, with a brace-piece provided with a tail-piece thicker than the said tie-plate and inserted beneath the lip *c*, so that as pressure is applied to the tie-plate the brace-piece will be firmly locked in position, substantially as described.

In testimony whereof I have signed my name to this specification in the presence of two subscribing witnesses.

GEORGE H. BARGE.
